CLAIM

The ornamental design for a watch, as shown and described.

DESCRIPTION

FIG. 1 is a front elevational view of a watch showing my new design; the broken-line showings of straps being environmental only and form no part of the claimed design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

FIG. 2

FIG. 1

FIG. 3

FIG. 4

FIG. 5

FIG. 6
